GARMENT HANGER

Eric J. Ajax, Minneapolis, Minn.

Application February 11, 1946, Serial No. 646,783

9 Claims. (Cl. 211—96)

1

This invention relates to garment hangers and more particularly to an improved hanger that may be used for suspending trousers, skirts or the like.

It is an object of the invention to provide an improved garment hanger of the suspension or bracket type and to provide a single or multiple wall mountable garment hanger. It is a further object of the invention to provide an improved garment hanger construction which is capable of holding garments of widely varying thicknesses and to provide a hanger construction which is capable of being used in a suspension type hanger or bracket type hanger. It is a further object of the invention to provide an improved article of manufacture capable of being fabricated into hangers of the suspending or bracket type.

Other objects of the invention are the provision of an improved, all metal, hanger construction of especially stable type capable of being manufactured at low cost from readily available materials.

Other and further objects of the invention are those inherent in the apparatus herein illustrated, described and claimed.

The invention is illustrated with reference to the drawings in which

Figure 1 is a plan view of a multiple hanger of the wall mounting type;

Figure 2 is a front view of the apparatus shown in Figure 1;

Figure 3 is an enlarged fragmentary sectional view taken along the lines 3—3 of Figure 2;

Figure 4 is an enlarged fragmentary sectional view taken along the lines 4—4 of Figure 1;

Figure 5 is a side elevational view of a modified form of the invention showing the hanger of the hook type; and

Figure 6 is a plan view of the apparatus shown in Figure 5.

Throughout the drawings corresponding numerals refer to the same parts.

Referring to the drawings the hanger which may be of either the wall mounting single or multiple type or of the hook type utilizes the same basic hanger unit. Referring to Figure 1, each hanger element is composed of a main hanger strip generally designated 10 which is preferably of metal bent into the form of a pivot eye, as shown at 11, and is provided with two extending legs 12 and 13. Leg 12 is the longest and forms one of the garment gripping surfaces. It is provided with an offset portion at 14 and has a bent end at 15 so as to permit easy entrance of the garment into the hanger as hereinafter de-

2

scribed. The leg 13 extends from the eye 11 and in a direction away from leg 12 along portion 16 and is then bent at 17 in a direction so that it gradually approaches the leg 12 where its end 18 is terminated at approximately the middle of the offset 14 of the leg 12. The resiliency of the member 10 causes the leg 13 normally to move towards the leg 12. The entire member 10 may be formed cold or may be formed and then heat treated to obtain the desired strength and resiliency properties. The end of the leg 13 is provided with a rectangular aperture 20 as shown in Figures 1, 2 and 3, and through the aperture there is attached a clip 21 which is riveted at 22 to the center of a gripper bar generally designated 25. The gripper bar forms the second garment gripping surface and is preferably made of channel shaped strip having a cross section, indicated at 25 in Figure 4. The width of the channel 25 is such that the end 18 of the short leg 13 is received within the channel flanges 25A and 25B, and thus the gripper bar 25 is provided with reinforcement against misalignment at the pivotal attachment 20—21. At the same time the gripper bar is able to oscillate freely in the direction of arrows 26 and 27, and thus the ends 28 and 29 of the gripper bar 25 are permitted to move into contact with the long leg 12 of the hanger or against any thickness of garment that is placed in the hanger. The gripper bar is provided with an offset bend at 30 which corresponds to the offset 14 so as to provide a space for the seams of trousers and the like which usually occur at approximately the center of a trouser leg.

The basic hanger element just described is used in either the hook type hanger shown in Figures 5 and 6 or in a single or multiple wall mounting type hanger of the type shown in Figures 1 and 2. Where used in the single or multiple wall mounting there are provided a pair of angularly disposed bracket plates 32 and 33 which are provided with one or more apertures to receive screws 34 by which the brackets are attached to a vertical surface such as a wall or door. The bracket plates 32 and 33 extend horizontally at 36 and 37 and are spaced apart a distance sufficient to receive the width of the strip 10 of the hanger and provide slight clearance. A pivot is provided at 38, and is preferably of tubular form having an outer diameter 39 of which fits snugly into the pivot loop or eye 11 of the hanger. As illustrated in Figure 4 the pivot 38 is a tube which is turned down at each end 40 so as to provide shoulders which are received in apertures of the same size in the horizontal por-

tions 36 and 37 of the bracket. The rivet is then spun down, as illustrated, and is firmly locked to the bracket plates, and thus holds them in spaced relationship. The distance between the shoulders 41 and 42 is such that the plates 36 and 37 are maintained apart a distance just slightly greater than the width dimension D of the hanger member 10. Hence, the hanger moves freely about the stationary pivot 38 and the pivot forms a spacing element for the plates 36 and 37, and hence holds them immovable.

Where a single hanger element 10 is utilized the bracket plate is shaped so as to provide room for only one pivot 38. However, the preferred construction includes two or more hangers 10, four being illustrated in Figure 1. When thus mounted the surfaces 36 and 37 of the hangers are cut diagonally along the line 45 and the pivots 38 are inset from this edge by a suitable distance along the line 46—47. The spacing between the pivots illustrated at dimension S is made sufficient so that the hangers 10 when loaded will lie parallel to each other, as illustrated for the hangers 10, 10A and 10B in Figure 1 and for the dotted line position of hanger 10C. Enough spacing is allowed so that the hangers will lie parallel to each other when loaded with a garment of maximum thickness capable of being handled by the hanger.

When it is desired to load or unload the hanger, it may be swung to the position shown in full lines for hanger 10C and the garment may thus be readily inserted through the outwardly divergent tips 15 and 31. The hanger is moved apart at tips 15 and 31 and this causes the bar 25 to pivot on its rear tip 29, forcing the long and short legs 12 and 13 apart. As the garment is drawn fully into the space between the long leg 12 and the gripper bar 25, the gripper bar levels out and stabilizes against the garment, regardless of usual variations in thickness from side to side of the garment. Any of the hangers 10A, 10B and 10C may be pivoted outwardly for loading and unloading, and when loaded or in the idle position they may be swung back to the position shown in Figure 1 so that the garments or idle hangers are thus brought parallel to the surface on which the hanger 32—33 is mounted.

In the modification shown in Figures 5 and 6 the basic hanger element 10 is provided with a hook made of strip material 50 having a hook portion 51 of a size such that it may be hung upon the usual closet rod or pole. The depending portion 52 of the hook has a widened lower portion 53 at the bottom through which there are inserted spaced rivets 54 by which the hook is fastened to the offset 14 of the hanger element. In this way the hanger element is immovably attached to the hook.

As many apparently widely different embodiments of this invention may be made without departing from the spirit and scope thereof, it is to be understood that I do not limit myself to the specific embodiments herein except as defined by the appended claims.

What I claim is:

1. A garment hanger comprising a resilient member bent in the form of a pivot eye and having integral horizontally spaced generally parallel long and short portions extending from said eye, the short portion being terminated at about the middle of the long portion, and a gripper bar pivotally attached at about the middle thereof to the end of the short portion of the resilient member, said bar being positioned so as to be in

resilient gripping relation against the long portion of the resilient member.

2. A garment hanger comprising a frame bar of resilient strip metal, said strip being bent so as to form a pivot-loop with long and short ends extending therefrom, said long end being straight throughout the major portion of its length, said short end being bent adjacent the loop so as to extend a short distance away from the long end 10 adjacent the loop and then gradually towards the center portion of the long end, a stiff garment gripper bar having a width approximately equal to the width of the frame bar and a length approximately equal to the long extending end 15 thereof, said gripper bar being pivotally attached adjacent its center to the short end of the frame bar and positioned between said short and long ends so as to be urged against the long end by the resiliency of the short end, the connection 20 between the gripper bar and the terminus of the short end being such that the gripper bar is maintained aligned with the short end and the long end.

3. The apparatus of claim 2 further characterized in that the long end and the gripper bar are offset away from each other at their middle portions.

4. The apparatus of claim 2 further characterized in that the gripper bar is of C-shaped channel cross section with its open side away from the long end of the frame bar and of a width such that the short end of the frame bar nests in the channel.

5. A garment hanger comprising a resilient member bent in the form of a pivot eye and having integral horizontal spaced generally parallel long and short portions extending from said eye, the short portion being terminated at about the middle of the long portion, a gripper bar 35 pivotally attached at about the middle thereof to the end of the short portion of the resilient member, said bar being positioned so as to be in resilient gripping relation against the long portion of the resilient member, and means 40 attached to said resilient member for supporting the garment hanger.

6. A garment hanger comprising a resilient member bent in the form of a pivot eye and having integral horizontally spaced generally parallel long and short portions extending from said eye, the short portion being terminated at about the middle of the long portion, a gripper bar 50 pivotally attached at about the middle thereof to the end of the short portion of the resilient member, said bar being positioned so as to be in resilient gripping relation against the long portion of the resilient member, and a bracket having a vertically positioned pivot extending through the pivot eye in said resilient member.

7. A garment hanger comprising a frame bar of resilient strip metal, said strip being bent so as to form a pivot-loop with long and short ends extending therefrom, said long end being straight throughout the major portion of its length, said 60 short end being bent adjacent the loop so as to extend a short distance away from the long end adjacent the loop and then gradually towards the center portion of the long end, a stiff garment gripper bar having a width approximately equal to the width of the frame bar and a length approximately equal to the long extending end thereof, said gripper bar being pivotally attached adjacent its center to the short end of the frame bar and positioned between said short and

70 long ends so as to be urged against the long end

by the resiliency of the short end, the connection between the gripper bar and the terminus of the short end being such that the gripper bar is maintained aligned with the short end and the long end, and means attached to the resilient strip for supporting it substantially horizontal and with the axis of the pivot-loop portion substantially vertical.

8. A garment hanger comprising a frame bar of resilient strip metal, said strip being bent so as to form a pivot-loop with long and short ends extending therefrom, said long end being straight throughout the major portion of its length, said short end being bent adjacent the loop so as to extend a short distance away from the long end adjacent the loop and then gradually towards the center portion of the long end, a stiff garment gripper bar having a width approximately equal to the width of the frame bar and a length approximately equal to the long extending end thereof, said gripper bar being pivotally attached adjacent its center to the short end of the frame bar and positioned between said short and long ends so as to be urged against the long end by the resiliency of the short end, the connection between the gripper bar and the terminus of the short end being such that the gripper bar is maintained aligned with the short end and the long end, a bracket having parallel horizontal plates above and below the frame bar and a pivot extending through said plates and through the pivot-loop of the frame bar.

9. A multiple garment hanger comprising a bracket having means thereon for attachment to a vertical surface, said bracket including a horizontal plate having a plurality of vertical axis pivots mounted thereon, a plurality of garment hangers one pivotally mounted on each of said pivots, each garment hanger including a frame bar of resilient strip metal, said strip being bent so as to form a pivot-loop with long and short

ends extending therefrom, said long end being straight throughout the major portion of its length, said short end being bent adjacent the loop so as to extend a short distance away from the long end adjacent the loop and then gradually towards the center portion of the long end, a stiff garment gripper bar having a width approximately equal to the width of the frame bar and a length approximately equal to the long extending end thereof, said gripper bar being loosely attached adjacent its center to the short end of the frame bar and positioned between said short and long ends so as to be urged against the long end by the resiliency of the short end, the connection between the gripper bar and the terminus of the short end being such that the gripper bar is maintained aligned with the short end and the long end, each of said hangers being mounted upon one of the pivots of the bracket with the pivot through the pivot loop of the hanger, said pivots being horizontally spaced apart a distance to allow the hangers to be swung on their pivots to positions substantially parallel to each other and substantially parallel to the vertical surface.
